ERASER MOUNTING FOR PENCILS

Wilhelm Schäfer, Nurnberg, Germany, assignor to A. W. Faber-Castell, Stein near Nurnberg, Germany, a German firm

Application November 7, 1955, Serial No. 545,484

Claims priority, application Germany November 26, 1954

6 Claims. (Cl. 120—38)

The present invention relates to new improvements in eraser mountings for pencils.

For convenience in making corrections it has been known for a long time to provide one end of pencils with a small eraser which usually was secured thereto by means of a socket, preferably of metal, which was fitted to the pencil so that the rubber eraser formed an extension thereof. For securing the eraser socket to the pencil, one end of the latter was usually milled off or otherwise reduced in diameter so as to form a short cylindrical portion upon which the socket was fitted and then secured by punch marks. Although this type of eraser mounting was very inexpensive, it had the annoying disadvantage that, when using the eraser, the connecting socket would easily come loose from the pencil. At first it would wiggle when being used and eventually come off the pencil entirely. On the other hand, when using sockets of plastic material, this manner of mounting them on the pencils by means of punch marks could not be used at all, and therefore attempts were made to secure the plastic socket by means of an adhesive cement. However, it was found that because of the necessary wall thickness of the plastic socket and the fact that in fitting the socket on the pencil the cement was partly squeezed out, the pencil became both clumsy and ugly. The result was a considerable reduction in customer appeal and a loss in sales value of the pencils.

In order to prevent the excessive amount of cement, it has been suggested to supply it by means of a pump. Although this usually prevented the cement from emerging from the socket, it still did not result in a neat and secure connection.

It is the object of the present invention to overcome these disadvantages of the prior art and to provide a neat and secure connection of the eraser socket on the pencil by providing at least one of the connecting parts, that is, either the wooden end of the pencil or the socket, or both, with suitable depressions or grooves for taking up and retaining the cement therein, thus permitting an adequate amount of such cement to be supplied to the connecting surfaces to insure a secure connection, and preventing the cement from emerging from the socket.

A feature of the invention consists in the provision of such grooves in the form of interconnected channels extending in a direction either longitudinally or transverse of the pencil or in both directions. These channels will insure a proper distribution of the cement over the connecting surfaces of both pencil and socket and thus a secure and neat connection of the socket on the pencil.

Another feature of the invention applicable to pencils of polygonal cross section consists in partly removing the angular edges thereof and in applying the longitudinal channels between the surfaces intermediate such edges and the inner wall of the socket which is thereafter attached thereto. This will render a separate insertion of channels into the wood of the pencil unnecessary.

Another preferred feature of the invention resides in providing transverse channels within the socket, prefer-

2

ably by molding circular grooves into the cylindrical surface thereof. The stability of the connection may be further increased according to the invention by making the inner diameter of the socket and the diameter between two diagonally opposite broken edges of the pencil end of equal size so that, when connected, the socket will be in direct engagement with the pencil along these broken edges.

Another object of the invention is to provide a method and suitable means for injecting the cement into the channels of the two connecting parts after the same have been attached to each other. For this purpose, the invention provides a suitable pump which permits the injection into the channels of just the proper quantity of cement required and which is preferably provided with an annular groove immediately adjacent and in front of the nozzle end thereof which forms a constriction of the nozzle and allows an easier and cleaner separation of the cement therefrom so that the proper amount of cement may thus be supplied.

Another feature of the invention consists in the use of a cement in the form of an adhesive of viscous, readily applicable consistency, preferably a watery dispersion of polyvinyl acetate as commonly used as a synthetic adhesive for gluing wood. After being inserted into the channels, the viscosity of such a cement prevents the same from running out of its own accord, and insures its uniform distribution within the channels.

Such distribution of the cement within the channels after the same has been applied by means of the pump is preferably carried out according to the invention by forcing the rubber eraser into the socket on the pencil. The eraser then functions in the socket like a piston sliding in a cylinder and compresses the cement into the channels. The small residue remaining between the contacting surfaces after the eraser has been inserted also secures the latter within the socket to the end of the pencil. The accurate dosage of cement supplied by the pump insures that all channels will be completely filled and that no cement will emerge at the socket ends.

Further objects, features, and advantages of the present invention will appear from the following detailed description thereof which is to be read with reference to the accompanying drawings, in which

Fig. 1 shows a plan view of an eraser mounted on a pencil by means of a socket according to the invention;

Fig. 2 shows a plan view of the end of a pencil, the projecting corners of which have been partly milled off;

Fig. 3 shows a central longitudinal section through a pencil with a socket attached thereto;

Fig. 4 shows a similar section through a pencil with a socket attached thereto and a cement pump inserted into the socket;

Fig. 5 shows a cross section taken along line V—V of Fig. 2;

Fig. 6 shows a cross section taken along line VI—VI of Fig. 1;

Fig. 7 shows a cross section taken along line VII—VII of Fig. 1; while

Fig. 8 shows a cross section taken along line VIII—VIII of Fig. 1.

Referring to the drawings, and first to Figs. 1 to 5, the projecting corners of one end or terminal of a pencil 1 of the customary hexagonal cross section and containing a lead 1' are partly milled off to provide outer surfaces 3. A socket or ferrule 4 for securing the eraser 2 to the pencil 1 is slid over the milled surfaces 3 which are substantially circular and serve as seating surfaces for the socket. The gaps which are then formed between the socket 4 and the surfaces 3 remaining intermediate the partly milled-off seating surfaces 3 form the longitudinal channels 6 which are interconnected by

transverse channels 7 provided in the seating surfaces of the socket 4, the latter seating surfaces tightly engaging the seating surfaces 3 on the terminal of the pencil.

After sliding the socket 4 to the inner end of the milled surfaces 3, as shown in Fig. 3, the nozzle 9 of a cement pump 8 is inserted into the open end of socket 4, and a certain quantity of cement 10 is injected therein and against the blunt end or front side 11 of the pencil 1. Nozzle 9 has an annular groove 13 immediately adjacent the nozzle end 12 which facilitates the separation of the cement 10 from nozzle 9. When the tightly fitting eraser 2 is then pushed into the open end of socket 4, it will act like a piston sliding in a cylinder and force the cement 10 through the longitudinal channels 6 in the direction toward the inner end of the milled portion 3 and at the same time into the transverse channels 7 which are communicating with the longitudinal channels 6. The quantity 10 of cement as originally applied by the pump 8 on the blunt end of the pencil accurately complies with that needed to fill the longitudinal and transverse channels 6 and 7 without danger that any cement will be forced out of the socket end 14. The thin layer of cement finally remaining on the blunt end or front side of pencil 1 as well as the cement which has passed into the transverse channel 16 adjacent to the inner end or front side of eraser 2 firmly secures the same to the pencil both at such end as well as along its peripheral surface.

Figs. 6 to 8 illustrate the pencil 1 with the socket 4 enclosing the same. As previously mentioned, the surfaces 3 are formed by milling off a part of the projecting corners 17. The cement injected and distributed within the longitudinal and transverse channels 6 and 7 fills out these channels completely and, after hardening, forms a solid and secure connection between the eraser 2 and the pencil 1.

Although my invention has been illustrated and described with reference to the preferred embodiments thereof, I wish to have it understood that it is in no way limited to the details of such embodiments or to the specific examples described, but is capable of numerous modifications within the scope of the appended claims.

Having thus fully disclosed my invention, what I claim is:

1. A pencil having a ferrule partially sleeved over to seat on one of the terminals of said pencil, said ferrule partially extending from said pencil terminal and being provided with an opening at its free end, a rubber eraser inserted in said opening and held in that part of said ferrule, at least one of the interengaging seating surfaces of said ferrule and said terminal having longitudinal and the other of said surfaces having transverse channels, said longitudinal and said transverse channels respectively intersecting one another, and a cement filling said channels to firmly secure said ferrule to said pencil terminal at the points of intersection.

2. A pencil as set forth in claim 1, said transverse channels being in the interior surface of said ferrule and said longitudinal channels being in the exterior surface of said terminal.

3. A pencil as set forth in claim 1, said pencil having polygonal shape, the edges of the polygonal surface of said pencil being partially removed at said terminal to provide said channels between an otherwise substantially circular seating surface for said ferrule.

4. A pencil as set forth in claim 3, said terminal having a substantially circular cross section except for the flat edges left from the original polygonal shape, the exterior diameter of said circular section being substantially the same as that of the interior diameter of said ferrule.

5. A pencil as set forth in claim 1, the diameter of said terminal being slightly smaller than the largest dimension of the cross section through the other part of said pencil.

6. A pencil as set forth in claim 1, wherein said cement comprises a viscous mass capable of hardening and substantially filling the space within said ferrule intermediate adjacent front sides of said pencil terminal and said eraser to join said front sides to one another and to said ferrule.
